PNEUMATIC DISPATCH SYSTEM

Fred R. Taisey, Lowell, Mass., assignor to The Lamson Company, Syracuse, N. Y., a corporation of Massachusetts

Original application March 8, 1932, Serial No. 597,487. Divided and this application December 19, 1933, Serial No. 703,077

8 Claims. (Cl. 243—16)

This invention relates to improvement in pneumatic dispatch system and more particularly to a system comprising a main line, and a plurality of branch lines, which lines are oval in cross section; to means on the carrier which cooperate with means in the system at the junction points between the main line and the branch lines, whereby the carriers are dispatched to their desired destination by the coaction of such means; to a terminal by which the received carriers are presented to the operator at the station and to the form of carriers employed in such systems.

This application is a division of my copending application Serial No. 597,487, filed March 8, 1932, now Patent No. 1,965,933, issued July 10, 1934. The invention herein set forth is a development along the general lines of the inventions disclosed in the copending applications of William J. Taylor, Serial Nos. 597,439 and 597,440, filed March 8, 1932, and distinguishes therefrom by reason of the conformation of the tube and the coacting means on the carriers and in the system by which the course of travel of the carriers is controlled.

Several embodiments of this invention are described herein and illustrated in the accompanying drawings, in which:

Fig. 1 is a view in elevation of one form of terminal which may be employed in a system embodying this invention;

Fig. 2 is a top plan view of such terminal;

Fig. 3 is a side elevation of a carrier which may be used in a system having terminals of this type;

Figs. 4, 5 and 6 illustrate variations in the structure of the controlling means employed with carriers of the type shown in Fig. 3 to determine the destinations of the carriers;

Fig. 7 is a view similar to Figs. 4, 5 and 6, but on a larger scale illustrating another form of the control device which might be used;

Fig. 8 is a view similar to Fig. 1 illustrating another form of outlet terminal;

Fig. 9 is a sectional view taken along the line 9—9 of Fig. 8;

Fig. 10 is a front elevation with parts broken away of another form of delivery terminal;

Fig. 11 is a plan view of such terminal;

Figs. 12 and 13 are sectional views on enlarged scales taken along the lines 12—12 and 13—13 of Fig. 10;

Fig. 14 is a front elevation with parts broken away of a terminal station wherein the outlet terminal is enclosed within a receptacle;

Fig. 15 is a side elevation of the delivery por-

tion of the tube shown in Fig. 14, the enclosing receptacle being shown in section; and

Fig. 16 is a diagrammatic view illustrating a typical system embodying this invention.

As illustrated in Fig. 16, one form of system embodying this invention comprises a central station A and a plurality of outstations B, C and D. These stations are connected by a transit tube 30 which forms a closed circuit from the central station through each of the outstations and thence to the central station. The flow of carrier transporting air through the system may be set up in any desired way, as for example, by means of a suction blower E connected by a pipe 31 to the tube 30 at the outlet terminal of the central station. The tube 30 is provided at each station with an inlet terminal 32 and an outlet terminal 33. The outlet terminals 33 are here shown as connected to the main tube 30 by branch tubes 34 which may of course be of any desired length. It will be understood, of course, that the showing in this figure is merely diagrammatic and that the forms of terminals at the various stations may be changed as desired without in any way affecting the operation of the system embodying this invention.

The purpose of this invention, as suggested above, is generally that carriers introduced into the tube 30 at the inlet terminal 32 of the central station A will be deflected from the main tube 30 to the branch tube 34 which leads to the outlet terminal 33 of the selected outstation. Various means may be provided for determining the destination of the carriers and several such means have been illustrated in the drawings and will be described hereinbelow. As mentioned above, the tubes 30 and 34 are oval in cross section so that the carriers can not rotate on their longitudinal axes as they travel through the system.

Fig. 3 illustrates a carrier 80 applicable for use in this system and comprising heads 81 each having a notch 82 therein and, between the body of the carrier and each of the heads, wings 83, 84 or 85 (see Figs. 4, 5 and 6). These wings are pivotally supported upon pins 86 which connect the body of the carrier and the felt heads. It will be noted that the wings 83, 84 and 85 differ from each other primarily by reason of their length,

the wings 83, Fig. 4, being the shortest and the wings 85, Fig. 6, the longest. Referring to the system diagrammatically illustrated in Fig. 16, a carrier having the head shown in Fig. 4 will be delivered to the outstation B, one having the head shown in Fig. 5 will be delivered to the outstation

C and one having the head shown in Fig. 6 will be delivered to the outstation D.

In each head, one wing, here shown as the left one, terminates beyond the pivotal pin 86 in a tongue 87 which overlies a tongue 88 on the other wing. Furthermore, the tongue 87 extends into alignment with the notch 82 in the carrier head, and is held therein by spring means 89. Obviously, the exertion of inward pressure upon the tongue 87 will cause both wings to move simultaneously from the full line position illustrated in the drawings to the dotted line position. Advantage is taken of this fact in the operation of a system in which carriers of this type may be employed.

A typical outstation of a system employing such carriers is shown in Figs. 1 and 2. Here, as is the usual custom, the main transit tube 30 is interrupted and connected by a terminal casing 90 which may be in sections although not necessarily so constructed. In the opposite walls of the casing are formed curved recesses 91 which, as will be apparent from Fig. 2, are parallel to the major axis of the carrier head. Mounted in each recess 91 is a guide plate 92 which extends from the path of travel of carriers through the system to the closure valve 93. Pivotedly mounted in the casing 90 at the ingress end thereof is a cam 95 supported on a shaft 96 and normally held in the position shown in Fig. 1 by a spring 97. Referring to Fig. 2, it will be apparent that the cam 95 is so located that it will pass through the notch 82 of each of the carriers and thereupon engage the tongue 87 of the carrier wings. When a carrier destined for the particular station illustrated in Fig. 1 arrives thereat, the cam 95 acting upon the wings of that carrier force them into such a position that they will engage the guide strip 92 and the carrier thereupon is deflected from the main line and discharged. If, however, the carrier is intended for another station, the wings will not engage the guide strip 92, but may contact with the walls of the recesses 91, which by reason of the yielding mounting of the cam 95 causes no difficulty and the carrier travels on through the terminal casing to its destination.

In place of the type of wings illustrated in Figs. 4, 5 and 6, the carrier may be provided with a type of wing illustrated in Fig. 7, wherein the felt head 100, as before, is provided with a recess 101 at one end of the major axis. In place of pivoting the wings of each type of carrier upon the same pair of pins as previously described, and making the wings of different lengths, the wings may be all of the same length and mounted upon different pairs of pins. Thus, as shown in Fig. 7, the wings 102 are mounted upon pins 103, whereas the wings 104 and 106, illustrated in dotted lines, are mounted upon the pins 105 and 107. Each wing terminates in a tongue 110 and enters a notch 111 in a sliding plate 112. The plate is guided in its movement by pins 113 and is normally held by a spring 114 in the position in which it covers the notch 101. Upon the arrival of the carrier at any station, it will of course follow that the cam 95, acting through the notch 101, will depress the slide 112 against the urge of the spring 114 and force the wings on the carrier into the position shown in full lines in Fig. 7, so that if the carrier has arrived at its destination the wings 102 will engage the proper guides thereat. It will be understood that only one pair of wings are mounted upon each carrier, and that the destinations of the carriers are determined by the location of the wings.

Figs. 8 and 9 illustrate a typical station similar to that shown and described in Figs. 1 and 2 but differing therefrom in the fact that the cam by which the wings are actuated is fixed instead of being pivotally moved. In this type of station the portion of the transit tube 30 which enters the terminal casing 115 projects into the station to a considerable distance and is cut away as shown in Fig. 8 for reasons to be described later. Secured to the inner wall of this portion of the tube 30 is a stationary cam 116. The cam 116 is fixed to the wall of the tube by means of screws 117, which also act to secure a guide strip 118, such strip being, as shown in Fig. 9, of the same width as the cam 116 and thereby remaining in the notches 82 or 101 of the carriers. The station casing 115 is provided with lateral recesses 120, as is the station previously described, but such recesses are narrow and their locations in the various casings are changed. Opposite the cam 116 is provided a recess 121 in the casing (see Fig. 9). Extending in front of the recess 121 is a yieldable strip 122 which carries guide arms 123, such arms being integral or not, as desired, with the strip 122 and movable into and out of the cut-away portion of the tube to form substantially a continuation of the tube.

Mounted in the recesses 120 are guide plates 125 which obviously will receive and engage the tips of the wings of the carriers destined for that station, which tips enter the recesses 120. When, however, a carrier for another station arrives at this station, the expansion of the wings of the carrier by the action of the cam 116 is obviously prevented, since the tips can not enter the recesses 120. In order to avoid any possibility of stoppage of the system the spring strip 122 is provided which, with the arms 123, will yield and allow the carriers to pass by the cam 116. When a carrier destined for this station arrives thereat and the wings of the carrier are expanded by the stationary cam 116 so that they will engage the guide strip 125, it is possible that after the carrier head has passed the cam 116 the wings will return to their normal position and become disengaged from the guide strip. In order to prevent this action, the strip 118 is provided which remains in the groove of the carrier head until the carrier has been discharged from the system.

It has been found that conditions arise where in it is not feasible to provide the guiding notches at both ends of the carrier. This is particularly true when carriers of considerable length are employed and in order to insure that the carrier is properly deflected, supplementary means, such as is shown in Figs. 10 to 13 inclusive, may be employed. While these means are here shown and will be described as applied to a station unit of the type illustrated in Fig. 1, it will also be understood that the same means may be employed with other types of stations. The station unit comprises a pair of curved lateral recesses 130 in which are mounted guide plates 131 and a pivotally mounted cam 132 which enters the notch in the carrier head and expands the wings so that if the carrier is intended for delivery at this station the wings will come into engagement with the guide 131 and be deflected thereby.

Extending below the cam 132 but of the same width thereof is a narrow strip 135, the lower end of which rests upon an arm 136 mounted upon a pin 137. The pin 137 extends across the station unit and is connected by a link 138 to an arm 139, which arm is connected by a link

140 to a shaft 141 (see Fig. 11). The shaft 141 is parallel to the shaft 137 and like that shaft extends across the station unit, a recess 142 being preferably provided as shown in Fig. 10. 5 Fixed to the shaft 141 and normally lying within the recess 142 is a bar 143 preferably having its inner face curved. Upon the arrival of a carrier destined for this station the cam 132 will cause the wings at the head of the carrier to engage with the stationary guide 131 and the carrier will start to move toward the outlet, the spring plate 135 entering the notch and holding the wings in engagement with the guides. As the head of the deflected carrier reaches the end of 10 the strip 135 the latter is forced away from its normal position, thus swinging the finger 136 downwardly and through the mechanism previously described, causing the arm 143 to swing outwardly into the path of travel so that the rear end of the carrier is caused to follow the desired path and any stoppage of the system by cocking of the carrier in the line is prevented. The end of the strip 135 is so near the recesses 130 that the body of the carrier holds the finger 136 down 15 and prevents the arm 143 from leaving the path of travel until the whole carrier has been deflected. In place of the type of closure previously illustrated are shown a pair of closure plates 145 which function in substantially the same manner, being normally held in the position shown in Fig. 12 and expansible under the impact of the carrier to allow the carrier to be discharged into a receptacle 146.

In Figs. 14 and 15 is illustrated one embodiment of this invention wherein the transit tube 150 makes a U-shaped loop before entering the station casing 151 from which certain carriers are deflected and ejected past the outlet 152, normally closed by the flap 153. The looped portion of the tube is enclosed within a housing 155 into which the outlet 152 discharges the carriers. Supported in the housing is a trough 156 having an outwardly inclined base 157 onto which the carriers fall, and by which they are caused 20 to roll into a pocket 158 outside the terminal casing 155, from which they can easily be removed by the operator. As shown in these figures, there may be provided at the station a push-through inlet 159 of the type shown, described and 25 claimed in Patent No. 1,938,098 of Clark T. Cutting issued December 5, 1933.

While several embodiments of this invention have been shown and described, I am not limited thereto since other embodiments may be made without departing from the spirit and scope of the invention as set forth in the following claims.

I claim:

1. In a pneumatic dispatch system comprising a main transit tube, a plurality of stations along said tube, and carriers having movable wings thereon, adapted to travel through said tube selectively to the various stations, means for deflecting carriers to their destined stations comprising, at each station, guide strips and a cam, said cam acting upon the carrier wings to bring the wings of carriers destined for the station into engagement with the guide strips, whereby the carriers are deflected.

2. In a pneumatic dispatch system comprising a main transit tube, a plurality of stations along said tube, and carriers having movable wings thereon, adapted to travel through said tube selectively to the various stations, means for deflecting carriers to their destined stations com-

prising, at each station, guide strips and a cam, said cam acting upon the carrier wings to bring the wings of carriers destined for the station into engagement with the guide strips, whereby the carriers are deflected, said cam being yieldable under pressure of carriers destined for other stations.

3. In a pneumatic dispatch system comprising a main transit tube, a plurality of stations along said tube, and carriers having movable wings thereon, adapted to travel through said tube selectively to the various stations, means for deflecting carriers to their destined stations comprising, at each station, guide strips and a cam, said cam acting upon the carrier wings to bring the wings of carriers destined for the station into engagement with the guide strips, whereby the carriers are deflected, the cam being fixed and the station wall yieldable under pressure of carriers destined for other stations.

4. In a pneumatic dispatch system comprising a main transit tube, a plurality of stations along said tube, and carriers having movable wings thereon, adapted to travel through said tube selectively to the various stations, means for deflecting carriers to their destined stations comprising, at each station, guide strips and a cam, said cam acting upon the carrier wings to bring the wings of carriers destined for the station into engagement with the guide strips, whereby the carriers are deflected, and a bar which upon the arrival of a carrier is moved into the path of travel to guide the carrier to the station.

5. In a pneumatic dispatch system comprising a main transit tube, a plurality of stations along said tube, and carriers having movable wings thereon, adapted to travel through said tube selectively to the various stations, means for deflecting carriers to their destined stations comprising, at each station, guide strips and a cam, said cam acting upon the carrier wings to bring the wings of carriers destined for the station into engagement with the guide strips, whereby the carriers are deflected, a bar pivotally mounted in the tube, a strip below the cam and opposite the bar, and means connecting the strip and the bar, whereby the arrival of a carrier destined to that station causes said bar to swing on its pivot and assist in deflecting the carrier to the station.

6. In a pneumatic dispatch system comprising a main transit tube, a plurality of stations along the tube to which carriers are selectively dispatched and guide means associated with said stations for deflecting carriers thereto, a carrier having a head provided with a notch therein, wings pivoted upon the carrier, and means whereby the ends of the wings are projected beyond the edge of the head to engage the guide means associated with a station by means passing through the notch during the travel of the carrier.

7. In a pneumatic dispatch system comprising a main transit tube, a plurality of stations along the tube to which carriers are selectively dispatched and guide means associated with said stations for deflecting carriers thereto, a carrier having a head provided with a notch therein, wings pivoted upon the carrier, each wing having a tongue, the tongue of one resting upon the tongue of the other and extending into alignment with the notch whereby the ends of the wings are projected beyond the edge of the head to engage the guide means associated with a station by means passing through the notch and engaging the tongue in alignment therewith during the travel of the carrier.

8. In a pneumatic dispatch system comprising a main transit tube, a plurality of stations along the tube to which carriers are selectively dispatched and guide means associated with said stations for deflecting carriers thereto, a carrier having a head provided with a notch therein, wings pivoted upon the carrier, each wing terminating in a tongue, a sliding plate having notches therein which receive said tongues, said plate

being yieldably held in such position that one end thereof is in alignment with the notch whereby the ends of the wings are projected beyond the edge of the head to engage the guide means associated with a station by means passing through the notch and engaging the end of the plate in alignment therewith during the travel of the carrier. 5

FRED R. TAISEY.
